UNITED STATES PATENT OFFICE.

CHARLES F. STODDARD, OF BOSTON, MASSACHUSETTS.

METHOD OF MAKING NOTE-SHEETS FOR MUSICAL INSTRUMENTS.

1,370,614.

Specification of Letters Patent.

Patented Mar. 8, 1921.

Application filed November 15, 1911. Serial No. 660,435.

To all whom it may concern:

Be it known that I, CHARLES F. STODDARD, a citizen of the United States, and a resident of Boston, county of Suffolk, and State of Massachusetts, have invented an Improvement in Methods of Making Note-Sheets for Musical Instruments, of which the following description, in connection with the accompanying drawings, is a specification, 10 like characters on the drawings representing like parts.

This invention relates to prime controllers, such as note sheets, for governing the playing of automatic or partly automatic 15 musical instruments, as, for example, player pianos; and the invention comprises a new method of making such prime controllers.

Among other objects the invention is intended to provide for a substantially accurate 20 reproduction by an automatic instrument of characteristics of an actual manual rendition by an artist. It has been attempted heretofore to imitate in automatic playing some of the characteristics of manual 25 playing; for example, it has been a common practice to employ supplemental perforations in a note sheet for operating the loud or damper pedal mechanism of a piano, these supplemental perforations being 30 placed on the note sheet more or less arbitrarily by reference to the original musical score of the composition. Thus, a musician employed for the purpose would examine the score and indicate where the dampers 35 should be withdrawn from the strings and where they should be returned; and the perforations necessary for these purposes would then be correspondingly placed on the note sheet. Such a practice as this has, of course, 40 somewhat improved the automatic playing by providing for some sort of an automatic substitute for pedaling; but even so improved, the playing lacks that quality of spontaneity and individuality which characterizes a manual performance by an artist. 45 An artist's pedaling is largely instinctive and cannot be practically reduced to any rule which would enable one to translate an ordinary musical score into a perforated 50 note sheet and provide effectively for proper pedaling. In short, what has been attempted heretofore has had in view a mere imitation of characteristics of manual playing, as distinguished from actual reproduction 55 thereof such as contemplated by the present invention.

By contributing to the art a method and means of recording and reproducing characteristics of a manual performance, the present invention gives to an automatic instrument the capacity to reproduce (not merely imitate) the distinctive individuality of the greatest artists; and the public is afforded the opportunity to hear and study and analyze the actual expressions of the artist's 60 65 interpretative genius, instead of mere generalized imitations.

In the practice of this invention, a note sheet is made by reference to a substantially accurate record of characteristics of an artist's actual performance. A preferred form 70 of such record comprises adequate indications of the tempo peculiar to the artist's particular interpretation, and of the manner in which he employed the damper or sus- 75 taining pedal, or its substitute, in order to produce the sustaining effects which characterize his rendition. Such a record may be employed in accordance with this invention, in making a note sheet which shall reproduce automatically, with all necessary or desired fidelity, those characteristics of tempo and sustaining action which were largely accountable for the distinctive individuality of the original rendition. 80 85

It is a further object of this invention to provide a note sheet which shall be capable of reproducing pedaling effects, without requiring any auxiliary pedal perforations, or any automatic damper operating mechanism 90 in the playing instrument. This result is obtained in a preferred form of note sheet by characteristically prolonging the note perforations so as to sustain the individual notes sounded thereby with substantially the 95 same sustaining effects which were produced by the performing artist's pedaling.

The character of the invention may be readily understood by reference to an illustrative method and product thereof embodying the several features of the invention. 100

In the accompanying drawings:

Figure 1 represents diagrammatically suitable apparatus for making such a record as that above referred to; 105

Fig. 2 is a fragmentary view of a record made by the apparatus of Fig. 1;

Fig. 3 represents a note sheet such as may be made from a record of the type illustrated in Fig. 2.

The first step in the illustrative method about to be described comprises the making

of a record of characteristics of a manual performance and for this purpose it is preferred to employ some such recording apparatus as that shown in Fig. 1.

- 5 This illustrative apparatus is shown as associated with a piano key A, and a pedal B. Each of these may be of any suitable character as, for instance, the usual key, and loud or damper pedal of a piano.
- 10 The recording mechanism comprises electromagnets 5, 6, one for each key, and each having an armature 7 resting upon the upper end of a stylus 8 the lower end of which rests upon a sheet 9 of paper or other record receiving material. The record sheet 9 may rest upon a roll 10 and the latter may have upon its periphery a suitable recording medium, such, for instance, as a sheet of carbon paper.
- 15 The combined weights of the armature 7 and stylus 8 are insufficient to press the record sheet 9 against the recording medium on the roll 10 hard enough to make a mark on the former; when, however, the 20 electromagnet 5 is energized and the armature attracted, the stylus forces the record sheet 9 against the recording medium 11 and so long as the electromagnet 5 remains energized a line will be made upon the under side of the record sheet 9. The specific electromagnet 5 is shown as controlled by the pedal B, the operation of the magnet causing its stylus 8 to record the pedal operations as presently described.
- 25 It is preferred that the electromagnet 5 and its stylus 8 be positioned at or near one margin of the record receiving sheet 9 and that from said margin across the record receiving sheet the styli for the respective 30 notes be arranged in the same sequence and with the same spacing intended for corresponding perforations on the note sheet. With such an arrangement of styli, the 35 pedal record lines occur at or near a margin of the sheet and the lines recording the individual notes are positioned, transversely of the sheet, in the same relation in which the note perforations are to occur in the 40 finished sheet. It is also preferred that the record receiving sheet 9 be fed past the 45 styli at the same rate of speed at which the finished perforated note sheet is intended to be fed through a reproducing instrument. As will appear presently, this arrangement 50 of recording apparatus will indicate upon the record sheet exactly those relations of note perforations, and also the dimensions of the individual note perforations, by 55 which the recorded performance may be 60 reproduced.

Referring now to the key A, the same is provided with a contact point 20 the point of which is continuously immersed in a mercury bath in a cup 21. The cups 21 for 65 all of the keys may be mounted in a single

metallic strip which is connected by a wire 23 through a battery 24 to all of the electromagnets corresponding to the piano keys. The contact point 20 is connected by a wire 26, embedded in the key, with a second contact point 28 carried proximate the front end of the key and arranged to enter a mercury bath in a cup 30. There is a separate cup 30 for each key and each cup is insulated from the others and connected by 70 a wire 31 with the single corresponding electromagnet.

When the key is at rest as shown in Fig. 1, the circuit through the recording mechanism is broken between the contact point 80 28 and mercury cup 30; when the key is depressed, however, the point 28 enters the mercury bath in the cup 30 and closes the circuit from the battery 24 through the wire 23, mercury cup 21, contact point 20, wire 85 26 in the key, contact point 28, mercury cup 30, wire 31, to a single electromagnet 6 of the recording mechanism, and thence by a wire 35 back to the battery. This initial closing of the recording circuit preferably occurs at 90 an intermediate stage in the depression of the key; for instance, at substantially the time the hammer of its action strikes the string to sound its note. The closing of the circuit energizes the corresponding magnet, 95 causing it to press its stylus against the record receiving sheet and to initiate a line on the sheet which continues to be drawn so long as the circuit is maintained closed.

When the key is released, the contact 100 point 28 is withdrawn from the mercury bath 30 so as to break the circuit. This de-energizes the corresponding magnet and terminates the record line at substantially the time the damper is released by the key-action to damp the string unless prevented by the damper pedal being depressed at the same time.

This recording of the key movement by the illustrative apparatus may be readily 110 understood by reference to Fig. 2 in which a fragmentary view of such a record is shown; the arrow on the drawing indicates the direction in which the record sheet moves in making the record, corresponding 115 to the arrow shown in Fig. 1. As the key A is depressed, the first closing of the circuit by the contact point 28 starts the record line 40. So long as the key is held down, the record line continues but when the key is released and the circuit is broken by the contact point 28, the line 40 is terminated.

Thus, the end 41 of the line 40 indicates the beginning of the note and the end 42 125 indicates the release of the damper; accordingly the length of the line between the points 41 and 42 represents the time during which the note is held, by depression of the key, in the absence of a supplemental sus- 130

taining operation as by damper pedaling. In like manner, the line 44 provides a similar record of another note; the line 48 of another; 52 of another, 56 of another; and

5 so on.

The tempo by which an artist expresses his interpretation, is conspicuously characterized by the time relations in which he plays a succession of notes; in other words, 10 his individuality is expressed largely by the time relations of the initial sounding of the notes. These time relations are accurately indicated on the illustrative record by the points 41, 45, 49, 53, and 57. If, then, the 15 record sheet shown in Fig. 2 be provided with note-sounding perforations at the points 41, 45, 49, 53, 57, etc., respectively, they will initiate their notes in accordance with the tempo of the original manual rendition, 20 thereby faithfully reproducing one of the most distinctive characteristics of the latter.

In addition to the reproduction of the tempo of the original rendition, it is desired to reproduce the sustaining effects produced 25 by the performing artist, as by means of damper-pedal operations; and the illustrative apparatus of the drawings comprises means for recording the performer's pedaling. For instance, the pedal B is shown 30 diagrammatically as fulcrumed at 70 and having a pin 71 arranged to press a spring 72 into contact with a spring 73 when the pedal is depressed, as, for example, to remove the dampers from the strings of a piano. The 35 springs 72 and 73 are normally insulated from each other and the former is connected by a wire 74 through a battery 75 with the electromagnet 5, which is also in circuit with a wire 76 leading to the contact spring 40 73. Thus, when the pedal B is depressed the circuit is closed at the contact springs 72, 73, the electromagnet 5 is energized, and its stylus is caused to initiate a line which continues so long as the circuit is kept closed 45 by holding the pedal depressed. When the pedal is released the circuit is again broken and the record line terminated. The line so drawn represents the period of time during which the dampers are held off the 50 strings. For instance, the line 80 on the illustrative record of Fig. 2 indicates that the dampers were withdrawn from the strings just after the note corresponding to the line 40 was sounded and were held off 55 the strings until after release of the key corresponding to the lines 56. The effect of this damper-pedal operation, as well understood in the art, was to sustain all of the notes represented on the record even after 60 their individual keys had been released and their individual records terminated; in other words, the actual duration of a note played by the performer comprised not only the period represented by the record for the individual note (the distance 41 in Fig. 2, for

instance) but also an additional period represented by the length of the line 80 following the rear end of the individual note record.

Thus the described record indicates, by 70 the individual note records and the pedaling record taken together, not only the exact tempo relations in which the notes were initially sounded by the performer, but also the true durations of the notes exactly as 75 played in the original rendition and as sustained by the combined key and damper pedal operations. The manner in which the note sheet may be perforated to reproduce the tempo has already been described; it is 80 a further object of the invention to render the note sheet capable of reproducing substantially the sustaining effects resulting from the damper-pedal operation. Where the finished note sheet is intended for use 85 upon an instrument equipped with automatic damper-operating mechanism controlled from the tracker bar, a suitable damper-operating perforation or perforations may be provided in the note sheet in the positions indicated by the line 80 of the 90 described record. For example, if the automatic damper-operating mechanism requires a long, substantially continuous perforation for holding the dampers off the strings, a 95 continuous perforation having precisely the length and position of the line 80 could be provided. To suit other known types of damper-operating mechanism, the note sheet could be provided with a small perforation 100 for withdrawing the dampers, located at the advance end of the record line 80, and a small perforation for returning the dampers, located near the rear end of the line 80.

It is preferred, however, to adapt the note 105 sheet to use upon instruments which are not equipped with automatic damper operating mechanism, while retaining in the note sheet the capacity to reproduce automatically substantially the sustaining effects produced by 110 the performing artist's pedaling. This result may be obtained in the manner illustrated in the note sheet of Fig. 3. In this figure the perforations indicated in full lines are those which would be cut by reference to the individual note records such as those on the record sheet of Fig. 2, regardless of any sustaining pedal operation. The perforations indicated by dot-and-dash 115 lines at the left of Fig. 3 represent one form 120 of damper-operating perforations which would be provided preferably if the note perforations were cut as indicated in full lines—these full line note perforations and the dot-and-dash sustaining perforations 125 having the combined function (when used upon an instrument having automatic tracker-controlled damper mechanism) of playing the notes in the same tempo relations and with the same durations as those 130

of the original performance produced by the combined key and pedal operations.

To provide, however, for an instrument having no tracker-controlled damper mechanism, in which the dot-and-dash damper perforations would be of no avail, the individual note perforations are prolonged arbitrarily to sustain their notes as nearly as practicable with the same effect and to the same durations as produced by the performer's pedaling. For instance, in the original rendition of the composition represented by the note sheet of Fig. 3 (which is assumed to have been made from a record like that of Fig. 2) the note corresponding to the full line perforation 100 was sustained throughout the period represented by the dot-and-dash perforation 105. In order to reproduce this sustaining action in respect of that particular note, the perforation 100 is prolonged as indicated by the dotted line 103. The note initially sounded by the perforation 100 is intended to be re-sounded by the perforation 106; that is to say, in a player piano, for instance, there must be a second distinct percussion of the string caused by the perforation 106. To provide for this second percussion, the prolongation 103 of the perforation 100 does not extend all the way to the perforation 106 but terminates far enough from the latter to provide for the resounding of the note. The perforation 106 in turn is prolonged as indicated by the dotted line 107 sufficiently to sustain the note to the same duration indicated upon the record by the pedal record line corresponding to the dot and dash perforation 105. The hiatus between the prolongation 103 and the perforation 106 is preferably made so brief that the effect is little, if any, appreciated by the hearer, the result being to all intents and purposes that the note initially sounded by the perforation 100 is continuously sustained throughout the duration indicated by the perforation 105, just as it was sustained in the original rendition, the re-sounding of the note by the perforation 106 being introduced in the same time relation to the playing of the note 100 as in the original rendition.

In like manner, a perforation 101 having its advance end located in proper relation to the advance ends of the other perforations to reproduce the tempo of the original performance, has a prolongation 102 which sustains the note until terminated preparatory to re-sounding the same by the perforation 104 which again has a prolongation 108 which terminates preparatory to re-sounding the note by a perforation 109 having a prolongation 110. Thus, the perforations 101, 102, 104, 108, 109 and 110 sound and sustain and re-sound their notes with substantially the effect of the original rendition and in proper tempo relation to

the other notes. A perforation 111 sounds its note which is sustained by a prolongation 112 extending throughout the entire duration indicated by the dot-and-dash line 105.

The foregoing will suffice to illustrate to those skilled in the art the method by which a note sheet may be designed and perforated so as to render it capable of producing upon an ordinary piano player, for instance, having no tracker-controlled damper mechanism, substantially the tempo and pedal effects which characterize an actual manual rendition.

A note sheet of this sort could be made on the plan indicated in Fig. 3 by omitting the perforations 105, 115 and 116; and perforating the sheet for the individual notes alone, each note perforation having its advance end located as indicated for the advance ends of the full line perforations 100, 101 etc., and extending throughout the distance indicated by the dotted line prolongations. Thus, each note will be sustained substantially as it was sustained in the original rendition and will be played in exact accordance with the tempo of the original rendition, without requiring any auxiliary sustaining mechanism such as a damper-operating mechanism.

There is, of course, some difference between the sustaining effects produced by prolonging the individual note perforations as described, and those produced by the actual damper-pedal operation. As well understood in the art, the usual damper mechanism is such that when the damper pedal is depressed, the dampers are withdrawn from all of the strings simultaneously, permitting sympathetic vibration of all strings in response to the vibration of any string which may be sounded while the dampers are withdrawn. The initial impact of a hammer on a string, under such circumstances, will set up objectionable sympathetic vibrations, as well understood in the art. When, however, the sustaining is effected by the individual note perforations, the specific notes are themselves sustained and sympathetic vibrations occur in such other strings as are undamped at the time, while on the other hand, the discordant sympathetic vibration is eliminated, thereby avoiding an objection to the normal damper-pedal operation.

Whether or not any deliberate variation in intensity is provided for upon the sheet, by informative symbols or otherwise, the sustaining effects above described give, in actual playing, an effect of light and shade, as it were, in intensities, upon many types of playing instruments.

For example, when many notes are being sustained in the unusual manner provided for by the prolongations of a large proportion of the individual note perforations, each pneumatic playing action which is employed

in so sustaining a note, continuously bleeds from the supply of pneumatic pressure or exhaust and thereby tends to reduce such pressure or exhaust with a tendency to cause 5 succeeding notes to be sounded more softly. This tendency is, of course, increased as a greater number of notes are sustained and the effect is enhanced, to such an extent as to be readily appreciable, by the use of the 10 extensive note sustaining prolongations or perforations such as those illustrated in Fig. 3. While this effect of light and shade in intensity does not necessarily follow the variations in intensity of the original playing 15 by the performer, it nevertheless assists to an appreciable extent in eliminating the practically uniform intensity which contributes to the monotonous, mechanical quality of the playing my means of most 20 note sheets heretofore used.

In summary, the preferred form of note sheet contemplated by this invention, and having the prolonged note perforations, is adapted to reproduce with substantial 25 fidelity, the exact tempo of the original rendition, and the sustaining effects which the original performer produced by his pedaling; moreover this sustaining of the individual notes may result in such variation in 30 intensity as augments the pleasing effect of the playing.

It is to be understood that the invention is not limited to the specific details of the described illustrative method and note sheet. 35 It is not indispensable that the original record sheet itself be perforated, although this is convenient.

Claims:

1. A method of making a perforated note 40 sheet for reproducing upon an automatic musical instrument characteristics of a manual rendition, which comprises recording upon a record-receiving sheet moving at substantially the speed at which the finished note sheet is intended to be operated, a plurality of selected successive stages in the operation of the tone-sounding action for each of a plurality of tones sounded in the performer's rendition, including, first, a stage 45 substantially at the time of sounding the tone and, second, substantially the stage at which the tone-sounding action is released by the performer, the records of said two stages for each said tone being aligned and in 50 parallelism with corresponding records for other said tones; recording upon the same record-receiving sheet substantially the times when the damper pedal is depressed and released by the performer; and making 55 in the said sheet, perforations corresponding respectively to the tones recorded as aforesaid, each of said perforations having its advance end located at the record-mark of the first recorded stage aforesaid, and one 60 or more of said perforations having its rear

end extended arbitrarily beyond the record-mark of the second recorded stage aforesaid to sustain its note substantially as indicated by the record of pedal operations on said sheet.

2. A method of making a perforated note 70 sheet for reproducing upon an automatic musical instrument characteristics of a manual rendition, which comprises recording upon a moving record-receiving sheet, a plurality of selected successive stages in the 75 operation of the tone-sounding action for each of a plurality of tones sounded in the performer's rendition, including, first, a stage substantially at the time of sounding the tone and, second, substantially the stage at which the tone-sounding action is released by the performer; recording upon the same record-receiving sheet substantially the 80 times when the damper pedal is depressed and released by the performer; and making in a sheet perforations corresponding respectively to the tones recorded as aforesaid and having their advance ends relatively located in accordance with the relative locations of the record-marks of the first recorded stages 85 aforesaid, and said perforations having their rear ends extended arbitrarily regardless of the relative locations of the record-marks of the second recorded stages 90 aforesaid to sustain their notes substantially 95 as indicated by said record of pedal operations.

3. A method of making a perforated note 100 sheet for reproducing upon an automatic musical instrument characteristics of a manual rendition, which comprises recording upon a moving record-receiving sheet substantially the time of sounding each of a plurality of tones sounded in the performer's rendition; recording upon the same record-receiving sheet substantially the 105 times when the damper pedal is depressed and released by the performer; and making in a sheet, perforations corresponding respectively to the tones recorded as aforesaid, and having their ends relatively located in accordance with the relative locations of said records of sounding the tones, one or more of said perforations having its rear 110 end extended arbitrarily to sustain its note substantially as indicated by the record of pedal operations on said sheet.

4. A method of making a perforated note 115 sheet for reproducing upon an automatic musical instrument characteristics of a manual rendition, which comprises recording upon a moving record-receiving sheet substantially the times of sounding a plurality of tones sounded in the performer's rendition; recording upon the same record-receiving sheet substantially the times when the damper pedal is operated to sustain notes recorded as aforesaid; and making in a sheet, perforations corresponding respec- 120 125 130

tively to the tones recorded as aforesaid, and having their advance ends relatively located in accordance with the relative locations of said records of sounding the tones, 5 and having their rear ends extended to sustain their notes substantially as indicated by said record of pedal operations.

5. A method of making a perforated note sheet for reproducing upon an automatic 10 musical instrument characteristics of a manual rendition, which comprises recording upon a moving record-receiving sheet substantially the times of sounding the respective tones sounded in the performer's rendition; recording upon said sheet substantially 15 the times when the damper pedal is operated to sustain notes recorded as aforesaid; and making in a sheet, perforations corresponding respectively to the tones recorded 20 as aforesaid, and having their advance ends relatively located in accordance with the relative locations of said records of sounding the tones, substantially all of said perforations having their rear ends extended 25 far enough to cause their notes to be sustained through substantially the duration of the sustaining operation indicated by said record of pedal operations.

6. A method of making a perforated note 30 sheet for reproducing upon an automatic musical instrument characteristics of a manual rendition which comprises making a record of the time relations of the initial sounding of the respective tones sounded in the 35 performer's rendition; making a record of the times at and during which notes were sustained by the performer's pedaling; making in a note sheet note-sounding perforations relatively located in accordance with 40 said first named record; and adding to said perforations prolongations thereof for sustaining the notes through substantially the durations indicated by said second named record.

45 7. A method of making a perforated note sheet for reproducing upon an automatic musical instrument characteristics of a manual rendition which comprises making a record of the time relations of the initial 50 sounding of the respective tones sounded in the performer's rendition; making a record of the times at and during which notes were sustained by the performer's pedaling; making in a sheet perforations having their ad- 55 vance ends relatively located in accordance with said first named record and prolonging the majority of said perforations to sus- tain their notes and to position rear ends of perforations for sustaining the same 60 notes in substantially the same alinement transversely of the sheet and to terminate the notes substantially simultaneously in accordance with the end of a sustaining operation indicated by said second named record.

65 8. A method of making a perforated note

sheet for reproducing upon an automatic musical instrument, characteristics of a manual rendition which comprises making a record of the time relations of the initial sounding of the respective tones sounded in 70 the performer's rendition; making a record of the times at and during which notes were sustained by the performer's pedaling; and making in a sheet perforations having their advance ends located in accordance with 75 said first named record and prolonging said perforations substantially continuously to sustain their notes through substantially the duration of a sustaining operation indicated by said second named record.

80 9. A method of making a perforated note sheet for reproducing upon an automatic musical instrument characteristics of a manual rendition which comprises making a record of a manual rendition including 85 note sounding operations and damper pedal operations, making in a sheet note-sounding perforations having their advance ends relatively located in accordance with the tempo of said actual rendition; and sustaining perforations so positioned to sustain their notes substantially continuously throughout a period corresponding to a period of depression of the damper pedal in said actual rendition.

95 10. A method of making a perforated note sheet for reproducing upon an automatic musical instrument characteristics of a manual rendition which comprises making a record of a manual rendition includ- 100 ing note sounding operations and damper pedal operations, making in a sheet perforations having their advance ends relatively positioned in accordance with the tempo of said manual rendition; and having their 105 rear ends relatively located in accordance with the end of a pedal sustaining operation in said actual rendition.

110 11. A method of making a perforated note sheet for reproducing upon an automatic musical instrument characteristics of a manual rendition which comprises making a record of a manual rendition including 115 note sounding operations and damper pedal operations, making in a sheet note-sounding perforations having their advance ends relatively located in accordance with the tempo of said manual rendition; and sustaining perforations having their rear ends located 120 in accordance with the end of the pedal sustaining operation in said actual rendition.

12. A method of making a perforated note sheet for reproducing upon an automatic musical instrument characteristics of 125 a manual rendition which comprises making a record of a manual rendition includ- ing note sounding operations and damper pedal operations, making in a sheet note- sounding perforations having their advance 130

ends relatively positioned in accordance with the tempo of said actual rendition; and sustaining perforations for individual notes so sounded having their rear ends positioned in substantially the same line transversely of the sheet.

13. A method of making a perforated note sheet for reproducing upon an automatic musical instrument characteristics of a manual rendition which comprises making a record of a manual rendition including note sounding operations and damper pedal operations, making in a sheet note-sounding perforations having their advance ends relatively positioned in accordance with the tempo of said manual rendition, including perforations in the same line lengthwise the sheet for sounding and resounding the same note; and prolonging the advance perforation of two or more such aligned perforations to a point proximate the advance end of the second to produce the effect of sustaining the note substantially continuously between the sounding and resounding thereof, in accordance with a pedal sustaining operation in said actual rendition.

14. A method of making a perforated note sheet for reproducing upon an automatic musical instrument characteristics of a manual rendition which comprises making a record of a manual rendition includ-

ing note sounding operations and damper pedal operations, making in a sheet note-sounding perforations having their advance ends relatively located in accordance with the relative times of depressing the keys for the respective notes in said actual rendition, and having their rear ends arbitrarily extended to produce a pedal sustaining effect, without regard to the time relations of release of the keys in said actual rendition.

15. A method of making a perforated note sheet for reproducing upon an automatic musical instrument characteristics of manual rendition which comprises making a record of the time relations of sounding the respective notes in the manual rendition; making a record of damper-pedal operations in said rendition; making in a sheet note-sounding perforations having their advance ends relatively located in accordance with said first named record; and making in said sheet sustaining perforations located in accordance with said second named record.

In testimony whereof I have signed my name to this specification in the presence of two subscribing witnesses.
